UNITED STATES PATENT OFFICE.

DAVID M. GRAHAM, OF BORDULAC, NORTH DAKOTA.

STACKER FOR HARVESTERS.

1,412,238.

Specification of Letters Patent. Patented Apr. 11, 1922.

Application filed May 14, 1917, Serial No. 168,533. Renewed July 11, 1921. Serial No. 483,948.

To all whom it may concern:

Be it known that I, DAVID M. GRAHAM, a citizen of the United States, residing at Bordulac, in the county of Foster and State 5 of North Dakota, have invented certain new and useful Improvements in Stackers for Harvesters, of which the following is a specification, reference being had therein to the accompanying drawing.

10 The invention relates to an apparatus for the stacking and maturing of cereal grains or the like, and consists in the parts and combinations thereof herein set forth and claimed, the same comprising a wheel supported means for forming and depositing a stack of the unbound straws and attached grain berries, adapted to travel with a cutting apparatus having grain carrying and distributing means by which the grain, as it 15 is cut, is delivered into the stack former.

Among the objects and advantages of the invention are the saving of time and labor in cutting and handling the grain preparatory to threshing; the better drying and 25 curing of the grain in loose form as distinguished from bound form; the saving of the expense incident to the binding system including cost of machinery and breakage or failure in operation of the same, with 30 consequent loss of valuable time in the limited harvesting season; repairs of binding machinery; the cost of binding twine; the loss of grain rattled out from the grain heads by such machinery and in handling the 35 bundles after binding; the further saving of labor and time in gathering up widely scattered bundles or small shocks, and also of time with respect to the occupation of the land by widely distributed harvested grain 40 which delays the preparation of the land for the next crop; and, in general, the substitution for all of these operations of machinery which is relatively simple and inexpensive, requiring few and simple repairs, and which 45 is nevertheless efficient in operation, in place of the more complicated and expensive machinery heretofore in general use. In addition to these considerations is the material improvement in the grain berries, in weight, 50 grade and value, which is of the greatest importance.

With such objects in view, as well as other advantages which may be incident to the use of the improvements, the invention consists in the parts and combinations thereof 55 hereinafter set forth and claimed, with the

understanding that the several necessary elements constituting the same may be varied in proportions and arrangement without departing from the nature and scope of the 60 invention.

In order to make the invention more clearly understood there are shown in the accompanying drawings means for carrying the same into practical effect, without 65 limiting the improvements, in their useful applications, to the particular constructions which, for the purpose of explanation, have been made the subject of illustration. In 70 the said drawings:

Fig. 1 is a side elevation looking at the near side of the stack forming and depositing apparatus.

Fig. 2 is a similar view looking at the off-side of the same.

Fig. 3 is a front view of the same.

Fig. 4 is a rear view of the same.

Fig. 5 is a plan view showing the base frame and the bottom of the stack former, the upper parts and the left-hand platform 80 87 being removed.

Fig. 6 is a vertical longitudinal section of the bottom portion of the stack former, the forward wheel support being omitted, on line VI—VI of Fig. 5.

Fig. 7 is a cross section of the ventilating space former of said bottom on a larger scale, on line VII—VII of Fig. 6.

Fig. 8 is a horizontal section, on a larger scale, at one of the rear corners of the stack former, on line VIII—VIII of Fig. 4.

Figs. 9 and 10 are longitudinal sections, on a larger scale, of a portion of the forward part of the frame, illustrating the means for securing and releasing the movable bottom of the stack former, on lines IX—IX and X—X respectively, of Fig. 5.

Fig. 11 is a vertical sectional detail on line XI—XI of Fig. 3.

Fig. 12 is a similar view on line XIII—XIII of Fig. 3.

Fig. 13 is a plan view showing a portion of the axle and one of the roller bearing supports for the movable bottom.

Fig. 14 is a sectional view on line 105 XIV—XIV of Fig. 13.

Referring to the drawings, the stack former body is carried by a base frame, and said frame is carried by ground wheels 1, arranged near the middle of the machine so 110 that the body is very nearly balanced, with a slight preponderating weight at the front

of the machine, the relatively light weight of the front end being suitably supported, preferably by a caster wheel 2. The base frame comprises side bars 3, inwardly inclined front members 4 and a front cross bar 5, the whole being preferably formed in one piece of angle iron. 6 is an arched frame member the lower part of which is secured to the bars 3 at the front of the same, 10 and 7 is a similar or somewhat higher arched member attached to the side bars at their rear ends and at the stack depositing end of the machine. 8 is a cross bar secured to the members 4 near the lower end of the arched member 6. 9, 9 indicate horizontal truss frames extending outwardly from the side bars 3, one at each side of the machine, attached by bolts 10 to the base frame at their front and rear ends, and also connected 15 therewith at intermediate points by horizontal frame members 11. The wheels 1 are arranged within said truss frames 9 and are carried on an axle 12 which extends across the machine under the base frame thereof 20 and is mounted in bearings 13, 14 (Fig. 4) which are attached to the under sides of the bars 3 and 9. 15 is a longitudinal frame member for the attachment of the front ground wheel 2, bolted to the frame members 8 and 5 (Fig. 5). It is provided with a vertical bearing 16 for the stem pivot 17 of the caster wheel. 18 is a collar fixed on the upper end of said pivot by a set screw 19 (Fig. 5). 20 is a draft attachment secured 25 to the front end of the base frame.

The side walls of the stack former are indicated at 21 and are mounted at their rear ends by hinges 22 on the rear arch 7, so that they may be moved outward and inward for 30 the release of a formed stack and to return to normal position. The front wall of the former is shown at 23 and fixedly attached to the front arch 6. The rear end of the former is closed for the forming of the stack 35 by an end gate 24 which is mounted near the top of the rear arch 7 by a transverse pivot rod 25 (Fig. 4).

The confining walls 21 and 23 and said end gate may be suitably constructed of boards, 40 sheet metal, lattice work, woven wire, or heavy canvas, as may be preferred. In the construction illustrated the side walls are formed of boards (Figs. 1 and 2), the front wall of a metal framework to which are attached vertical rods forming a lattice work (Fig. 3), and the end gate of a lattice work of wooden slats (Fig. 4). That side wall over which the grain is to be delivered to the former may have an outwardly inclined top 45 portion 26 (Fig. 3) to facilitate such operation.

The side walls are swung outward for a limited distance by links 27 arranged outside of the front wall 23 and pivotally connected 50 to 29 with brackets 30 which are bolted to

the inner sides of the front ends of the walls 21 (Fig. 11).

The pivots 29 in the brackets 30 pass from the inside to the outside of the stack former through a slot 31 in the front wall. This slot is formed by angle bars 32 which are bolted to the arch 6. The side walls are further controlled and guided and held from distortion by the weight of the stack by frames 33 which are bolted to the side walls 34 and carry at their inner ends forward projections which work in the slot 31. These projections are preferably formed by rollers 35 fitting in the slot, washers 37 which engage the inner and outer faces of the angle bars, and bolts 38 which pass through said washers and rollers and through the inner ends of the frames 33. The pivots 29 may have similar rollers 39 and washers 40. The links 27 are pivoted at 41 to the upper and lower arms of a lever 42 and the upper arm of said lever is formed to be operated by hand for the release of the stack and for the return of the side walls to their normal inward position. 43 is a fixed rack attached to the arch 6, by which the lever 42 is held in its adjusted position. Before the formation of a stack the lever 42 is so operated as to draw the forward ends of the side walls 21 inward until they are nearer together than are the rear ends, and the interior of the stack former flares rearwardly. When said forward ends are released and the stack is deposited the side walls and parts of the stack former become, or may be, further and further away from the sides of the stack as the machine moves forward from the stack so as to deposit the stack in as perfect form as possible and without undue friction.

The rear end gate 24 is held closed and 105 is released by arms 44 pivoted at 45 on brackets 46 which are bolted to the rear frame arch 7 (Fig. 8). The outer ends of said arms are connected by pivots 47 with the rear ends of rods 48. When the gate 110 is released to swing outward and upward for the deposit of a formed stack said parts assume the positions shown by dotted lines in Fig. 8. The rods 48 extend forward at the sides of the former (Figs. 1 and 2), 115 passing through guides 49 attached to frame members 50, 50'. Upper side frame bars 51 are attached to the arches 6 and 7. Inclined brace members 52, 53 connect the bars 51 with the arches 6 and 7 respectively, and 120 inclined brace members 54, 55 connect the bars 51 with the base bars 3, and are preferably riveted together at 56. The frame member 50 is attached to the side bar 51 and secured to the rivet 56, (Fig. 1) and the member 50' is attached to its side bar 51 and to the base bar 3. 56' indicates braces by which the base bars 3 are trussed and stiffened. 57 is a side foot board for the use 125 of an operator, 57' is a front foot board and 130

58 is a front platform, these parts being suitably attached to the frame of the machine. The forward ends of the rods 48 pass through guides 58 and are connected by pivots 59 with arms 60, which are fixed in a rock shaft 61 (Fig. 3). The latter is mounted in bearings 62 fixed on the frame members 4 (Fig. 5) and is oscillated at will by a lever 63. The upper parts of the arms 60 are connected by a cross bar 64 engageable by a vertically movable hand operated rack 65 to be held thereby in a rearward position, which holds the rods 48 and arms 44 in the positions shown in full lines in Fig. 8 with the end gate 24 closed. The lever 63 is stiffened by a truss 66 attached thereto (Fig. 2). After the end gate is released, by raising the rack 65 and pulling the lever 63 forward, it is swung rearwardly by the pull of ropes or chains 67 which are attachable in the desired ones of holes 68 in arms 69 forming parts of the end gate frame and extending upward and forward from the pivots 15. The ropes 67 pass over sheaves 70 and down to points of attachment at 71 on the downwardly movable bottom of the machine (Fig. 5), so that the first part of its downward movement opens the end gate for the deposit of the stack.

30 The main frame of the movable bottom of the stack former is shown at 72 (Fig. 5), consisting preferably of an angle bar bent into or constructed in U-form and arranged so that its middle part 73 is a cross bar near the bottom of the front wall 23 and its ends 74 extend rearward along the inner sides of the base bars 3. The axle 12 has mounted thereon, by means of anti-friction rollers 75, rotary sleeves 76 (Figs. 13 and 14), and on said sleeves rest inclined shoes 77 (Fig. 6). These shoes are attached to the under sides of the bars 74 so that the bottom frame 72 may roll rearwardly and forwardly by the rotation of the sleeves 76 and may tilt vertically thereon. The weight of the forward part of the frame does or may preponderate slightly so that it normally rests horizontal on the sleeves 76 and stops 78 (Fig. 5) which are attached to the bars 3. But the frame is 45 yieldably held forward by a spring 79 attached to the bar 8 and to rods 80, the latter being connected with a cross bar 81 of the frame 72. The tilting of the frame and the formed stack is started by the operator pressing up on the handle 81' the lower part of which extends down within the former and is attached to the bar 73. Not much pressure is required for this purpose, the bottom with a stack thereon being nearly balanced.

50 After so tilting for a small distance the frame 72 will slide backward, rolling on the sleeves 76 until arrested by stops 82 which engage said sleeves. In the meantime the frame 72 continues to tilt backward until the rear ends of the bars 74 or curved shoes 82' thereon rest on the ground. 83 is a cross bar having end rollers 83' which rest loosely on the flanges of the bars 74, and said bar is connected with the axle by links 84 and moves up and down with the bars 74. Longitudinal rods 85 rest on the bar 83 loosely so as to readily draw from under the stack as it is deposited, and are attached at their front ends to a cross bar or bars 86 of the frame 72, and are further supported and spaced by a cross bar 85' through holes in which they extend. Said rods support the rear part of the stack. 87 indicates a pair of platforms or supplemental bottom sections mounted one on each side of the front part of the frame 72. They are longitudinally movable or slidable on said frame, preferably by means of wheels or rollers 88, the axle 107 of which is held in bearings 108 on a cross-piece 106 attached to the under side 85 of the platform 87. The outer rollers run on the flanges of the bars 74 and the inner rollers run on longitudinal bars 88' which are framed with the cross bars 73 and 86 so as to be parts of the frame 72. The platforms 87 are held normally in a forward position as shown in Fig. 6 by springs 89 attached to the cross bar 8. As the rods 85 are drawn from under the formed stack the platforms 87 may remain for a time under the forward part of the stack. 90 is a catch adapted to hook over the front bar 73 (Fig. 9) to hold the frame 72 from rearward sliding. It is pivoted in a bearing 91 and lifted by the forward turning of an arm 92 when the latter is pulled by a link 93. 94 is a bolt sliding in bearings 95 and engaging over the bar 73 to hold the front end of the frame 72 from tilting upward. The bolt is withdrawn by a link 96 (Fig. 10). Said parts 93 and 96 are operated to release the platform by the lever 63 to which is connected a cross bar 97 (Fig. 5) to which latter said parts are pivoted.

98 is a space-former for producing an air ventilating opening or tunnel in the base of the stack of grain (Fig. 7). It is preferably composed of an interior frame 99 on which is fixed an exterior covering 100 of sheet metal, canvas or the like. Along the bottom edges of the former 98 are attached angle bars 101 which are attached to the cross bars of the frame 72 (Fig. 5). The rear lower corner of the former is beveled off as shown at 102 in Fig. 6 to prevent injury by contact with the ground, and is provided with movable side pieces 103, which may be of sheet metal, and which are pivoted to the former at 104 so that they will be swung up by contact with the ground and will drop back to the position shown in Fig. 6 when the former returns to the horizontal position.

The stops 78 are preferably rollers mounted on the base frame, on which the frame 72 may roll freely forward after it has assumed a horizontal position. Attached to 130

the under sides of the platforms or tables 87 are bumpers or stops 105 adapted to engage the frame bar 86 to limit the rearward movement of the tables, and adapted to engage the bar 73 when the tables are in their normal forward position. The top boards of said tables are attached to the front and rear wheel-carrying cross pieces 106. The tables are preferably covered on top with 10 galvanized iron which becomes very smooth in use so that the tables readily disengage from under the formed stack leaving it intact.

What is claimed is:

15. 1. In a former for stacking cut grain, the combination of a wheeled support, side walls on said support and arranged to leave an open space at the rear end for the sliding and exit of the formed stack, a bottom which is 20 tiltable upward at its inner end relative to said side walls, and a transverse member under said bottom arranged at a distance from its front end and extending between and having means of connection with said side walls.
20. 2. In a former for stacking cut grain, the combination of a wheeled support, side walls on said support arranged to leave an open space at the rear end for the exit of the 30 formed stack, a bottom which is tiltable upward at its inner end and downward at its rear end relative to said side walls, and a transverse axle for ground wheels under said bottom and arranged near the median trans- 35 verse line thereof and extending between and having means of connection with said side walls.
30. 3. In a former for stacking grain, the combination of a wheeled support, stack con- 40 taining walls having a rear opening for the deposit of a stack, a bottom having rear- 45 wardly movable stack-supporting rods adapted to be moved downward into contact with the ground, and a cross support under said rods relative to and on which the rods are longitudinally movable for the deposit of a stack.
40. 4. In a stack former for harvesting ma- 50 chines, a bottom comprising a vertically tilt- 55 ing and longitudinally slidable frame, an axle on which said frame is adapted to slide and tilt, a front stack-supporting bottom part which is longitudinally slidable on said frame, and a space former on said frame.
50. 5. In a stack former for harvesting ma- 60 chines, a bottom comprising a vertically tilt- 65 ing and longitudinally slidable frame, an axle on which said frame is adapted to slide and tilt, a front stack-supporting bottom part which is longitudinally slidable on said frame, and longitudinal rods on the rear part of said frame.
60. 6. In a stack former for harvesting ma- 65 chines, a bottom comprising a vertically tilt- 70 ing and longitudinally slidable frame, an

axle on which said frame is adapted to slide and tilt, a front stack-supporting bottom part which is longitudinally slidable on said frame, and a space former on said frame, said front bottom part consisting of sections 70 at each side of the space former.

7. In a stack former for harvesting ma- 75 chines, a bottom comprising a vertically tilt- 80 ing and longitudinally slidable frame, in- 85 clined shoes on said frame, a support on which said shoes are adapted to slide and tilt, and a front stack-supporting bottom part which is longitudinally slidable on said frame.

8. In a stack former for harvesting ma- 80 chines, a longitudinally slidable and ver- 85 tically tilttable bottom which is movable up- 90 ward at its front end and downward at its rear end, having thereon a space former, and comprising a front stack-supporting part 95 which is movable relative to said space former.

9. In a stack former for harvesting ma- 90 chines, a longitudinally slidable and verti- 95 cally tilttable bottom, having thereon a space former and comprising a front stack sup- 100 porting member which is longitudinally movable relative to said space former, a spring for drawing and automatically re- 105 turning said front part forward to normal 110 position, an axle along the median part of said tilttable bottom, and means for arresting the rearwardly sliding movement of said bottom relative to said axle.

10. A stack former bottom, having thereon 100 a space former, a stack supporting member which is longitudinally movable relative to the space former, means for automatically returning said stack supporting member to normal forward position, and a cross axle 105 arranged along the median portion of said bottom.

11. In a stack former for harvesting ma- 110 chines, the combination of a base frame, ground wheels carrying the said frame at 115 the sides thereof, a transverse axle for the said ground wheels, rotary roller-bearing sleeves on the axle, a tilttable bottom frame nearly balanced on the said sleeves and rear- 120 wardly movable thereon by the rotation of the said sleeves, rearwardly extending rods attached to the said tilting frame, a space former carried on the tilting frame, stack- 125 supporting platforms rearwardly movable on the tilting frame at each side of the space former, and means for returning the tilting frame and said platforms to forward position.

12. In a stack former for harvesting ma- 125 chines, the combination of a base frame, ground wheels carrying the said frame at 130 the sides thereof, a transverse axle for the said ground wheels, a tilting bottom frame nearly balanced on the said axle and rear- 135 wardly movable thereon, rearwardly ex-

5 tending rods attached to the said tilting frame, a space former carried on the tilting frame, stack-supporting platforms rearwardly movable on the tilting frame at each side of the space former, and springs connecting the tilting frame and said platforms with the base frame for drawing them forward.

13. In a stack former for harvesting machines, the combination of a base frame, ground wheels carrying the said frame at the sides thereof, a caster wheel carrying the front end of the said frame, a transverse axle for the said ground wheels, rotary 10 roller-bearing sleeves on the axle, a tilting bottom frame nearly balanced on the said sleeves and rearwardly movable thereon by the rotation of the said sleeves, rearwardly extending rods attached to the said tilting frame, a space former carried on the tilting frame, stack-supporting platforms rearwardly movable on the tilting frame at each side of the space former, and springs connecting the tilting frame and said platforms 20 with the base frame for drawing them forward.

14. In a stack former for harvesting machines, the combination of a base frame, ground wheels carrying the said frame at the 30 sides thereof, a transverse axle for the said ground wheels, rotary roller-bearing sleeves on the axle, a tilting bottom frame nearly balanced on the said sleeves and rearwardly movable thereon by the rotation of the said sleeves, rearwardly extending rods attached to the said tilting frame, a space former carried on the tilting frame, stack-supporting

platforms rearwardly movable on the tilting frame at each side of the space former, and inclined shoes on said tilting frame adapted 40 to cause its forward movement after it has tilted back from its stack-depositing position.

15. In a stack former for harvesters, a longitudinally movable and vertically tilt- 45 able bottom member for supporting the forward part of the stack, a rearwardly extending bottom portion carried by said member, a support for said rearwardly extending bottom portion having means whereby it is held from rearward movement, and anti-friction devices whereby the rear part of said support rests on said tiltable bottom member.

16. In a stack former for harvesters, a bottom comprising a longitudinally movable 55 and tiltable frame, rearwardly extending rods carried by said frame, a support for said rods having means whereby it is held from rearward movement, and having at its rear part rollers which bear on said frame. 60

17. In a stack former bottom, the combination of a longitudinally movable and tiltable frame having rearwardly extending stack-supporting rods, and an upwardly and downwardly movable support for the rear 65 parts of said rods relative to which support said rods are longitudinally movable.

In testimony whereof, I affix my signature, in presence of two witnesses.

DAVID M. GRAHAM.
